UNITED STATES PATENT OFFICE.

EDGAR L. NICHOLS, OF GREELEY, COLORADO.

RADIATOR CAP.

Application filed March 29, 1923. Serial No. 628,595.

To all whom it may concern:

Be it known that I, EDGAR L. NICHOLS, a citizen of the United States, residing at Greeley, in the county of Weld and State of Colorado, have invented certain new and useful Improvements in a Radiator Cap, of which the following is a specification.

This invention comprehends vital improvements in filling caps for receptacles, radiators and the like and the primary object of the present invention is to provide novel means for associating the plug or cover of the cap with the body thereof and novel means for permitting the automatic 10 raising and lowering of the cover by the turning of an adjusting ring.

Another prime object of the invention is to provide novel means for holding the radiator cover or plug of the filling cap in 20 a raised or closed position against accidental movement, whereby the radiator or receptacle can be easily filled when so desired.

A further object of the invention is to provide a novel means for opening and closing the cover plates or plugs of the filling caps of radiators and the like, which will be durable and efficient in use, one that will be simple and easy to manufacture and one 30 which can be placed upon the market at a reasonable cost.

With these and other objects in view the invention consists in the novel construction, arrangement and formation of parts, as will 35 be hereinafter more specifically described, claimed and illustrated in the accompanying drawings, forming a part of this specification, in which drawings:

Figure 1 is a side elevation of the improved filling cap associated with the upper end of an automobile radiator, the radiator being shown in section.

Figure 2 is a diametric section through the improved filling cap showing the cover or plug in its lowered position.

Figure 3 is a similar view showing the plug or cover in its raised position.

Figure 4 is a horizontal section taken on the line 4-4 of Figure 3.

Figure 5 is a front elevation of the improved filling cap with parts thereof broken away and in section to illustrate the novel means employed for holding the plug or

cover on its feet against accidental movement.

Figure 6 is a plan view of the improved filling cap showing parts thereof broken away and in section.

Figure 7 is a rear elevation of the improved filling cap or plug showing the hand grip ring in section to illustrate the formation of the operating ring.

Figure 8 is a horizontal section through the improved device taken on the line 8-8 of Figure 3.

Figure 9 is a diametric section taken on the line 9-9 of Figure 8 looking in the direction of the arrow.

Figure 10 is a detail plan view of the spring washer to eliminate play in the various parts of the cap.

Figure 11 is a detail section through the spring washer.

Figure 12 shows detail views of the leaf springs employed for eliminating play between the various parts of the device.

Referring to the drawings in detail, wherein similar reference characters designate corresponding parts throughout the several views, the letter A generally indicates an improved filling cap and B a radiator with which the same can be used. The radiator B is of the ordinary or any preferred type generally employed in the cooling systems of internal combustion engines and embodies an upstanding sleeve 15 provided with internal threads 16 for receiving the cap, as will be hereinafter more fully described.

The improved filling cap A is particularly adapted for use with radiators of cooling systems of motor vehicles and has been shown in connection with a radiator B but it is to be understood that the cap can be used for other purposes. As shown the improved cap A embodies a cylindrical neck or body 20, the lower end of which is provided

with threads 21 for permitting of the convenient connection of the cap with the sleeve 15 of the radiator B. The extreme upper end of the body or neck 20 can be provided with an outwardly extending annular flange

22, which forms a limiting shoulder for the operating ring 23. The upper surface of the operating ring 23 is rabbeted as at 24 which provides a shoulder 25 for engaging

the lower surface of the flange 22. By referring to Figures 2 and 3 of the drawing it can be seen that the upper edge of the operating ring 23 extends at an appreciable 5 distance above the neck 20 and thus forms a seat for the plug or cover 26 of the improved cap. It is preferred to have a gasket 27 formed of some compressible material such as rubber, felt or the like fitted 10 upon the upper surface of the neck so as to permit a relatively tight joint to be had between the cover or plug 26 and the said neck. It is preferred to make the cover 26 of relatively heavy material and the cover or plug 15 26 can also be provided if so desired with an annular flange 28 for engaging the extreme upper edge of the operating ring 23 as clearly shown in Figures 2 and 3 of the drawings. The rear edge of the plug or 20 cover 26 can be cut away as at 29 and provided with a hinge barrel 30 and this hinge barrel 30 can be fitted in a suitable cavity 31 formed in the outer surface of the neck 20 at the rear edge thereof. As shown a 25 suitable pivot pin 32 extends through the hinge barrel and through the neck 20 adjacent to the upper end thereof. It is to be understood of course that the upper surface of the neck can be provided with bearing 30 lugs for receiving the said pivot pin 32. The operating ring 23 is held in position against accidental movement on the neck 20 and for rotary movement thereon by means of a supporting ring 34 and this supporting 35 ring 34 is secured to the neck 20 by suitable retaining screws or the like 35. An annular washer 36 formed of resilient material is disposed upon the upper surface of the retaining ring 34 and this washer has struck out 40 therefrom suitable resilient tongues 37 for engaging the said operating ring 23 and forms means for normally urging the ring upward so as to eliminate the loose play therein, and thus obviate rattling and the like. I also contemplate the use of double 45 ended leaf springs 38 which can be riveted or otherwise secured to the under surface of the flange 22 or to the shoulder 25 formed by the rabbeted portion 24 and these springs 50 serve the same function as the resilient washer 36. It is obvious that when it is desired to take apart the cap that it is merely necessary to remove the screw 35, slip off the retaining or supporting ring 34 and then pull 55 off the operating ring 23.

To permit the convenient operation of the operating ring 23 I provide a manipulating ring 40 which is in the nature of a hand grip and I contemplate the knurling the 60 outer surface of this manipulating ring so as to permit the firm grasping thereof by the hand of the operator. The manipulating ring 40 can be secured to the operating ring 23 in any preferred manner, such as by 65 a key 41, which can be placed in companion

keyways formed in the inner or meeting surfaces of the manipulating and operating rings. I prefer to make the manipulating ring 40 of a sufficient width or height to fully cover the supporting ring 34, so as to 70 hide the same from view of the ordinary observer. The operating ring 23 at the rear portion thereof is provided with a pair of spaced inclined slots 46 and 47. The slot 46 is disposed below the upper edge of the 75 operating rings while the slot 47 extends through the upper edge. The slot 46 has also its upper end terminating in a straight portion or slot 48 which lies in parallel relation to the upper edge of the said operating 80 ring.

The hinge barrel 30 is provided with opening and closing pins 49 and 50, which extend at different angles therefrom and when the cover or plug 26 is in its lowered position 85 the pin 49 normally lies within the slot 48 and this portion of the slot holds the cover in its closed position against accidental movement. Now when the operating ring 23 is turned in a counter clock-wise direction the pin 49 will ride into the slot 46 from the slot 48 and owing to the inclination of the said slot the pin will be forced downward, which will tend to raise the cover or 90 plug 26. It is obvious that as the cover swings to its raised position that the pin 49 will gradually swing out or away from the slot 46 and as the pin gradually moves from out of the slot, the pin 50 will be moved into the slot 47 and the inclination of this slot 95 will continue raising the cover or plug to its extreme raised position. This slot 47 and pin 50 cooperate with other means for engaging the pin 49 for causing the raising of the cover to its highest position and this additional means consists of an inclined surface 52 formed on shoulders 25 formed by the rabbeted portion 24 and an inwardly extending lug 53 having an inclined base 54. This lug 53 is attached in place on the inner 100 surface of the operating ring 23 by a suitable screw or the like. Thus it can be seen that the pin 49 will be engaged continuously during the raising movement of the cover. In order to insure of the continual engaging of the pin 49 with the curved face 54 of the lug 53 and the curved surface 52, an arcuate guide dog 55 is provided. This guide dog 55 is secured by means of a suitable pivot pin 56 to the operating ring 23. A suitable 105 spring can be provided for normally urging this dog into engagement with the pin. As clearly shown in Figure 8 of the drawings the outer surface of the sleeve 20 can be provided with a cam-shaped slot or groove 57 110 for the reception of the lug 53 and the dog 55.

In order to hold the cover in its closed position against accidental movement and tightly on its seat when the same is in its 115

lowered position, one or more radially extending locking pins 60 can be carried by the outer edge of the plug or cover 26. As shown only one pin 60 is provided and this pin is adapted to ride into a bayonet slot 61 formed in the operating ring 23 when the cover is moved to its lowered position by the said ring. It is obvious that when the pin 60 rides into the straight portion of the 10 bayonet slot, that accidental movement of the cover or plug 26 will be eliminated.

From the foregoing description it can be seen that an improved and simple device has been provided for raising and lowering the 15 covers or plugs of filling caps and for normally holding the covers or plugs in a lowered and raised position.

While the cap operates efficiently in its present form it is to be understood that refinements can be made thereto, such as the provision of rollers on the manipulating pins 49 and 50 and the provision of stop or limiting lugs on the cover or plug 26 and the manipulating ring 40.

Changes in details may be made without departing from the spirit or the scope of this invention.

What I claim as new is:

1. A filling cap comprising a sleeve, a pivoted cover secured to the sleeve, a manipulating ring rotatably associated with the sleeve and cooperating means between the cover and ring for causing the raising and lowering of the cover during manipulation 35 of said ring.

2. A filling cap comprising a sleeve, a pivoted cover secured to the sleeve, an operating ring rotatably associated with the sleeve, means for raising and lowering the 40 cover by the turning movement of said ring, and means for locking the cover in a raised or lowered position against accidental movement.

3. A filling cap comprising a cylindrical body, means for connecting the body to the vessel to be filled, a cover pivotally secured to the body, a rotatable manipulating ring mounted upon the body, said ring having inclined guide ways formed therein, and pins carried by the cover for fitting in said 50 guide ways whereby upon turning movement of the ring the cover will be raised or lowered.

4. In a radiator cap, a cylindrical body, a cover pivotally secured to the body, a ring rotatably mounted upon the body, the ring having an inclined guide way formed therein, a pin carried by the cover and arranged on one side of the pivot point thereof fitted 60 in said guide way, whereby upon movement of the ring the cover will be raised or lowered, and means for preventing movement of the ring longitudinally of said body.

5. A radiator cap comprising a cylindrical body, an annular outwardly extending

flange formed on the upper end of the body, a rotatable operating ring fitted upon the body arranged to engage said flange, a retaining ring detachably secured to the body and arranged to engage the lower end of 70 said first mentioned ring, and means operatively connecting the ring to the cover to permit the raising and lowering of said cover during rotary movement of said ring.

6. A radiator cap comprising a cylindrical body, an annular flange formed on the upper edge of the body extending outwardly therefrom, a pivoted cover secured to the body, a rotatable operating ring mounted upon the body and arranged to abut said flange, a retaining ring fitted upon the body for engagement with the lower surface of said operating ring, means securing the retaining ring of the body against movement, means operatively connecting the rotatable 85 ring with the cover to permit raising and lowering of the cover during rotation of the ring, and a manipulating ring detachably secured to the operating ring and arranged to cover the operating ring and said retaining 90 ring.

7. A radiator cap comprising a cylindrical body, a cover pivotally secured to the body, a manipulating ring rotatably associated with the body having an inclined 95 guide way formed therein terminating at its upper end in a straight guide way, a pin carried by the cover at one side of the pivot point thereof for fitting in said guide ways, 100 and for the purpose specified.

8. A filling cap comprising a cylindrical body, an outwardly extending flange formed on the upper edge of the body, a rotatable operating ring fitted on the body having a rabbeted portion to receive the flange, means for holding the ring against said flange, a cover, a hinge barrel formed on the cover, a pivot pin extending through the barrel and said body, a pin extending outwardly from said hinge barrel beyond said pivot pin, the ring having a guide slot therein to receive said pin, and an inclined face below said slot, a guide pin carried by the inner surface of the ring arranged below the inclined face, and a pivoted guide dog carried by the ring for engaging said pin during the movement thereof.

9. A filling cap comprising a cylindrical body, a pivoted cover for the body, a rotatable ring mounted upon the body operatively connected to the cover for raising and lowering the same during rotary movement therein, a retaining pin formed on the cover, the rotatable ring having a bayonet slot therein arranged to receive the pin when the cover 120 is in its lowered position for preventing accidental opening movement of said cover.

10. A radiator cap comprising a body, a flange formed on the upper end of the body and extending outwardly therefrom, a ro-

rotatable operating ring mounted upon the body having a rabbeted portion arranged to receive the flange a pivoted cover, means operatively connecting the ring with the cover to cause the cover to raise and lower during rotary movement of the ring, a supporting ring secured to the body and arranged to engage the lower surface of the rotatable ring, and a resilient washer disposed between the

retaining ring and the rotatable ring, and leaf springs disposed between the flange and said rotatable ring.

In testimony whereof I affix my signature in presence of two witnesses.

EDGAR L. NICHOLS.
